(57) **CLAIM**

The ornamental design for a blind clip, as shown and described.

DESCRIPTION

FIG. 1 is a perspective view of the blind clip according to the invention;

FIG. 2 is a front view of the blind clip, as shown in FIG. 1;

FIG. 3 is a rear view of the blind clip as shown in FIG. 1;

FIG. 4 is a left side view of the blind clip as shown in FIG. 1;

FIG. 5 is a right side view of the blind clip as shown in FIG. 1 shown from the opposite side as that shown in FIG. 4;

FIG. 6 is a top view of the blind clip as shown in FIG. 1;

FIG. 7 is a bottom view of the blind clip as shown in FIG. 1;

FIG. 8 is a perspective view of the blind clip attached to a blind base; and,

FIG. 9 is a front view of the blind clip showing how to attach to a blind base.

The broken lines shown in the figures are for illustrative purposes only and form no part of the claimed design.
